UNITED STATES PATENT OFFICE.

JOHN E. CRANNY, OF OMAHA, NEBRASKA.

ATTACHMENT FOR LINE-CASTING MACHINES.

1,405,498.

Specification of Letters Patent.

Patented Feb. 7, 1922.

Application filed April 4, 1921. Serial No. 458,194.

To all whom it may concern:

Be it known that I, JOHN E. CRANNY, a citizen of the United States, residing at Omaha, in the county of Douglas and State 5 of Nebraska, have invented certain new and useful Improvements in Attachments for Line-Casting Machines, of which the following is a specification.

This invention has for its object to provide a device which may be applied to line casting machines to prevent injury to the liners. The device may be used in connection with any line casting machine in which printing-slugs or bars are cast in a slotted 15 mold and delivered therefrom by an ejector-blade moving from the rear against the edge of the slug, the liners being removably placed in and occupying a part of the molds, said liners being variable in length to produce slugs for use in printing columns or 20 pages of different widths. While the invention may be used to advantage in connection with the commercial Mergenthaler linotype machine, it may be applied to any 25 analogous machine.

The invention consists of the novel construction, combination and arrangement of parts as described herein and claimed, and as illustrated in the accompanying drawings, 30 it being understood that changes in size, form, proportions and minor details, may be made if desired, said changes to be within the scope of the invention as claimed.

In instances where frequent changes are required to form slugs which vary in length the liners must be manually changed by an operator, and while said liners are suitably numbered to visibly indicate their length, mistakes occasionally occur in their selection, 40 the result being that the liners become injured or broken since the length of a selected liner may not correspond with the length of movement of the sliding-bar, the distance to which the latter moves operating 45 to control the number of ejector-blades or ejector sections which move into engagement with the slug.

By use of the herein described device injury of a liner will not occur, since the sliding-bar will have a movement corresponding to the length of the slug to be ejected, and the ejector-sections will not engage the liner.

In the drawings, which illustrate one embodiment of the invention, Fig. 1 is a broken away view showing the front side of a mold-

ing-disc and certain mechanism mounted upon the frame of a line casting machine. Fig. 2 is a plan view of a rock-lever. Fig. 3 is an enlarged detail, partly broken and in section, showing a plunger-bar and parts connected therewith. Fig. 4 is a plan view, partly broken away and in section, showing parts of a line casting machine with the device mounted thereon. Fig. 5 is a detail relating to Figs. 1 and 4, being a view in side elevation of the ejector case and parts connected therewith. Fig. 6 is a view in front elevation showing a part of the machine frame and parts of the device mounted thereon. Fig. 7 is a plan view of the parts shown in Fig. 6, a part of a molding disc being added. Figs. 8 to 13 inclusive are side views of liners. Fig. 14 is a sectional view on line 14—14 of Fig. 13.

Referring now to the drawing for a more particular description, the attachment is shown and described in connection with the molding-disc 1, the rock-shaft 2 known as the distributor mechanism space-band arm-shaft, the machine frame 3, the ejector-blade control rod 4 and the sliding-bar 5 which moves the ejecting-blades 6 forwardly in the casing 7 of a line-casting machine.

Numerals 8 (Figs. 8 to 13) indicate liners of various lengths, and it will be understood that, in instances where comparatively a narrow column and short slug is required, a liner 8 is selected by an operator and is placed in the mold 9, the liner thus selected being of greater length than would be used in forming slugs for a wide column. It therefore follows, that the length of a slug a depends upon the length of the liner selected, since the part unoccupied in the mold 9, by the liner, is the part in which the slug is formed or molded, and it also follows that if a liner having too great a length is placed in the mold, the forwardly movable ejector-blades 6 which operate to move the slug from the mold, will engage and will injure the liner.

In order that injury to the liners may be avoided certain features of construction are provided which are of a simple nature and will be practical and operative in use, and now to be described.

The liners are provided with apertures b , the diameter of the aperture of each liner being specific and differing from that of the other liners. Numeral 10 indicates a plunger-bar provided at one of its ends with a

tapered pin 11, said pin preferably being removably mounted upon said bar by a keeper 12. The plunger-bar is slidingly mounted in brackets 13 which are secured to 5 the frame, and is so disposed that when the molding-disc moves and disposes the mold 9 at ejecting position (Figs. 1, 4), said bar will be disposed adjacent and at right-angles to the liner.

10 Numeral 14 indicates a spring operative for moving the plunger 10 in a direction of the liner 8 to cause the pin 11 to enter the aperture *b* of the liner, subject to a control of certain devices.

15 I provide an arm 15 which is mounted upon the rock-shaft 2 of the machine, said arm, during one of the movements of said shaft engaging a projection 16 of the plunger-bar and moving said plunger outwardly 20 against the force of the spring 14, the movement of the rock-shaft 2 in the opposite direction operating to release the plunger-bar and to permit it to slide toward the molding disc, said sliding movement, however, being 25 subject to the control of a bellcrank 17 having an arm *c* adapted to engage in a recess *d* of the control-rod 4.

30 A rock-lever 18, pivotally mounted at *e* upon the machine frame has an arm *f* engaging in a slot *g* of the plunger-bar, its opposite arm being pivotally connected with a link *h* having a pivotal connection with the control-rod 4, and it will be understood that if the bellcrank is moved against the 35 force of its spring *m* (Fig. 7.) so that its arm *c* will be released from the recess *d* the plunger-bar will have a forward movement to permit the tapered pin 11 to enter the aperture *b* of the liner.

40 Numeral 19 indicates a spring connected with the machine frame and with the rock-lever 18, said spring having a lesser degree of resiliency than the spring 14, but operative, when the spring 14 is extended, to move 45 the control-rod 4 upwardly to permit engagement of the arm *c* of the bellcrank in the recess *d* of the control rod 4. At 20 is indicated a rock-shaft having one arm *n* pivotally connected with the control-rod 4 and having an arm *p* which carries a rod 50 21 (Fig. 5.) which carries the sliding-bar 5.

55 As thus described the bellcrank operates as a stop for preventing any longitudinal movement of the control rod 4. In operation, the movement of the molding disc longitudinally of its axis is depended upon for releasing the arm *c* of the bellcrank from the recess *d*, the molding-discs of line casting machines having such forward movement of 60 approximately one-half of an inch after they move to ejecting position; and in operation, the disc, when moving forwardly, will engage one arm of the bellcrank and will cause a swinging movement thereof against 65 the force of its spring *m*, with the result

that its arm *c* will be released from the recess *d*, this release occurring after the mold 9 is disposed at the ejecting position.

In operation, a swinging movement of the arm 15 outwardly from the molding disc 70 will cause an outward movement of the plunger-bar 10 and the pin 11 against the force of the spring 14, the control rod 4 moving upwardly by operation of the spring 19, until the recess *d* receives the arm *c* of the bellcrank 17. The arm 15 then has a swinging movement toward the molding disc, but the plunger-bar will not be moved by action of the spring 14 since the arm *f* of the rock-lever 18 engages an adjusting-plate *s* of the plunger-bar, the bellcrank 80 operating to prevent any downward movement of the control-rod 4, and the plunger-bar will remain stationary until the molding-disc, while in ejecting position, moves forwardly in line with its axis, and causes the release mentioned of the arm *c* from the recess *d* of said rod 4; and as soon as this release occurs the plunger-bar, by action of the spring 14, will move forwardly, its 85 tapered pin 11 entering the aperture *b* of the liner.

90 By referring to Fig. 14 it will be seen that the walls of the apertures *b* are formed inclinedly, this feature being of advantage 95 to prevent undue wearing away of the walls which might be occasioned by engagements if the tapered pin therewith. However, the parts are so proportioned that while the pin enters apertures *b* with a certain force, said 100 force is sufficient only to insure suitable engagement.

105 It is obvious that the distance to which the plunger-bar and pin will move forwardly will depend upon the diameter of the apertures *b* of the liners, and it is apparent that the distance to which the rod 4 will be moved downwardly will depend upon the extent of the forward movement of the plunger, and these are desirable features since the upward 110 movement of the sliding-bar 5 will correspond, as to distance, with the downward movement of the rod 4. It follows, therefore, that the number of ejector-blades 6 to be moved forwardly in the casing 7 will depend upon the size of the apertures *b* provided for the liners 8, the movements of the rod 4 and bar 5 being greater if the size of the aperture in a liner is greater, and their movements being lesser if the liner is provided with an aperture of lesser size; for instance, if a liner has a length adapted for use in forming a column requiring 10 ems, said liner will have an aperture *b* so proportioned that the tapered pin may enter such a distance that the bar 5 will move upwardly far enough for moving the requisite number of ejector blades forwardly for engaging a slug representing 10 ems in length, the remaining ejector blades not being disturbed; 120 125 130

and if a liner used has a comparatively large aperture adapted for use where a column of 20 ems is required, it is obvious that the bar 5 will be moved upwardly a greater distance than in the first instance mentioned.

The use of the device will be appreciated by operators of linotype machines since there will be no uncertainty in operation or risk of breakage or injury of the comparatively 10 expensive liners; also no attention of an operator will be required for adjusting the ejector control-rod 4.

While in the drawing I have not shown the mold 9 to be provided with any aperture 15 for receiving the tapered pin, to permit the liner and its apertured terminal, during operation, to be disposed within the mold, and while in Fig. 1, I have shown a liner having a terminal part extending somewhat above 20 the mold 9, this feature is not material, and I may provide apertures b in any desired part of the liners.

I claim:

1. A line casting machine provided with 25 an apertured liner, and a tapered pin movable for entering the aperture of the liner and for actuating the ejector blade control rod.

2. In an attachment for a line casting machine having a mold and an ejector blade control rod, an apertured liner adapted to be disposed in the mold, and a slidably mounted plunger having a tapered part, said plunger being movable to cause its tapered 35 part to enter the aperture of the liner and to cause actuation of the ejector blade control rod.

3. An attachment for a line casting machine, comprising an apertured liner adapted 40 to be placed in the mold of the machine, a tapered pin movable longitudinally for entering the aperture of the liner and to cause a longitudinal movement of the ejector control rod of said machine, and means for limiting the longitudinal movement of the tapered pin for limiting the longitudinal movement of the ejector blade control rod.

4. In combination with the mold, the ejector blades, the sliding-bar and the ejector 50 blade control rod of a line casting machine, said control rod having a connection with the

sliding-bar, of an apertured liner adapted to be placed in the mold, and a tapered pin movable for entering the aperture of the liner and for moving the control rod to actuate the sliding-bar. 55

5. In an attachment for a line casting machine having a mold, an ejector blade control rod, a sliding-bar to be moved by the movement of the control rod, and having 60 ejector blades disposed in a plane between the mold and sliding-bar, of an apertured liner in said mold, and a tapered pin movable for entering the aperture of the liner and for moving the control rod. 65

6. In an attachment for a line casting machine having a mold and an ejector control rod, a liner adapted to be disposed in the mold, and a slidably mounted plunger-bar adapted to be reciprocated longitudinally for 70 moving the control rod, said liner and plunger-bar having co-operating parts adapted to enter into engagement when the plunger moves in one direction for limiting the movement of the control rod. 75

7. In combination with the mold, the ejector blades, the sliding-bar and the ejector-blade control rod for moving the sliding-bar transversely of the ejector blades, of a liner adapted to be placed in the mold, and a 80 longitudinally movable plunger, said liner and plunger having co-operating parts adapted to enter into engagement when the plunger moves longitudinally for limiting a movement of the control rod. 85

8. In an attachment for a line casting machine having a mold, an ejector blade control rod, a sliding-bar to be moved by the movement of the control rod and having ejector blades disposed in a plane between the mold 90 and sliding-bar, of a liner in said mold and a longitudinally movable plunger in bearings, said liner and plunger having co-operating parts adapted to enter into engagement when the plunger moves longitudinally for limiting the movement of the control rod. 95

In testimony whereof, I have affixed my signature in presence of two witnesses.

JOHN E. CRANNY.
